United States Patent Office

Des. 214,424

Patented June 17, 1969

214,424

JAR

Gerald W. Neese, Compton, Calif., assignor to Purex Corporation, Ltd., Lakewood, Calif., a corporation of California

Filed Sept. 5, 1967, Ser. No. 8,499

Term of patent 14 years

Int. Cl. D9—01

U.S. Cl. D9—92

FIG. 1.

FIG. 2.

FIG. 4.

FIG. 3.

FIG. 5.

FIG. 1 is a front elevational view of a jar embodying my new design;

FIG. 2 is a top plan view;

FIG. 3 is a bottom plan view;

FIG. 4 is an enlarged fragmentary view taken on the line 4—4 of FIG. 1; and

FIG. 5 is a fragmentary cross sectional view thereof taken on the line 5—5 of FIG. 1.

I claim:

The ornamental design for a jar, substantially as shown.
